UNITED STATES PATENT OFFICE

RALPH Z. HOPKINS AND EARL FENTON SEGER, OF DETROIT, MICHIGAN, ASSIGNORS TO
HUDSON MOTOR CAR COMPANY, OF DETROIT, MICHIGAN, A CORPORATION OF
MICHIGAN

STRIPING DEVICE FOR AUTOMOBILE BODIES

Application filed April 23, 1928. Serial No. 272,072.

This invention relates to a device or apparatus for striping automobile bodies and is adapted particularly for applying a stripe to or along the belt panel molding or window reveals of said body.

An object of the invention is to provide a device or apparatus of the foregoing character capable of producing an even and continuous stripe upon an automobile body, and to provide improved means for guiding the device in use, whereby stripes may be applied to the body at different positions relative to the belt line molding and window reveals.

15 A further object of the invention is to provide a striping device which may be easily guided over the body to be striped and in which the guiding means will not only yield in the event of any slight irregularities in the surface over which the guide travels, but will tend to hold the applicator away from the surface being striped. This construction tends to induce a uniform application of pressure by the workman in order to operate the device thereby resulting in the formation of a more uniform stripe and hence enabling the work to be done more efficiently by unskilled labor.

The above and other objects of the invention will be apparent from the following description and appended claims when taken in conjunction with the accompanying drawing wherein like reference characters designate corresponding parts in the several views.

35 In said drawing:

Fig. 1 is a perspective view of the device of our invention.

Fig. 2 is a longitudinal section of the device of Fig. 1.

40 Fig. 3 is a side elevation of the applicator and guide embodying our invention, with the parts extended for the purposes of clearness.

Fig. 4 is a detail perspective view of the clamp and adjusting screw for the pen.

45 Fig. 5 is a section taken along the line 5—5 of Fig. 3.

Fig. 6 is a side elevation of the applicator provided with a modified form of guiding device.

Fig. 7 is a plan view taken along the line 7—7 of Fig. 6.

Before explaining in detail the present invention, and the method or mode of operation embodied therein, it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation, and it is not intended to limit the invention beyond the terms of the several claims hereto appended or the requirements of the prior art.

The striping device or apparatus of our invention comprises preferably a body portion 10 having a reservoir 11 provided with a removable cap or closure 12 having an air vent 13 therein. A handle 14 depends below the body portion. The body portion is additionally provided with a forwardly extending threaded nipple 15 and a rearwardly extending threaded nipple 16, and with a rearward extension 17. The reservoir is separated from the interior of the body portion by means of a partition wall or diaphragm 11a having therein one or more apertures 11b to permit fluid to pass from the reservoir to the body.

Threaded upon the forward nipple 15 is one form of applicator which may be employed comprising a relatively fixed portion 18 and a rotatable portion 19, these parts being held together by means of a ring 20 and being mounted for relative non-frictional rotation through the medium of an interposed set of ball bearings 21. The rotatable portion 19 of the applicator carries a pair of pivoted nibs 22, 22 which together provide the adjustable pen of the present applicator. These nibs are preferably hinged at 23 to the portion 19. A feed tube 24 extends through the parts 18 and 19 to a point adjacent the tips of the pen nibs 22. The nibs 22 are maintained in fixed relation by means of a clamp 25 provided with an adjusting screw 26,

whereby the nibs may be adjusted relatively to one another and to the feed tube 24.

The rear nipple 16 is provided with an apertured cap 27 threaded on to the nipple and positioned between this cap and the nipple is 5 packing material of any suitable character 28. A needle valve 29 having a step 30 extends through the cap and nipples 16 and 15 and is adapted to seat in the conical inner end 10 of the feed tube 24. The stem carries a pair of fixed stops 31 and 32. The rear body extension 17 is internally threaded to receive 15 an adjusting screw 33 bored to receive a coil spring 34 which surrounds the valve stem 30 and which engages the stop 32. By turning the screw 33 against the action of the spring 34 it will be seen that the valve 29 is yielding- 20 ly maintained against its seat.

An operating lever 35 is provided for opening 25 the valve 29 in order to supply fluid in proper amount to the pen in accordance with the speed at which the device is moved over the body panel. This lever is pivoted by means of a pivot screw 36 to the body por- 30 tion 17 and comprises a forwardly bent arm 37 terminating in a thumb piece or button 38 in position to be pressed by the thumb of the workman when grasping the handle 14. The inner end 39 of the lever extends between the 35 stop 31 and the cap 27. By pressing the button 38 the end 39 of the lever will force the stop 31 and hence the valve stem 30 rear- 40 wardly against the action of the spring un- 45 seating the valve to permit flow of fluid to 50 the applicator.

It will be noted that the operating device 55 which controls the valve may be actuated during the striping operation to increase or decrease the amount of paint applied to the 40 body. This is important in enabling the amount of paint fed by gravity to the pen to be increased or decreased in accordance with the speed in which the device is moved by the operator over the body. Inasmuch as the operator's thumb engages the thumb piece 38 during the striping operation, as he increases the speed in which the device is moved over the body, it is merely necessary to operate the valve 29 which will result in more paint being 50 forced by gravity into the pen. Thus, it will be seen that the device 35 provides means under the control of the operator for regulating the amount of paint being fed to the pen in proportion to the speed in which the device 55 is moved over the surface of the body.

Referring now to Figs. 1 to 5 inclusive, the guide in the present instance comprises preferably a socket portion 40 pivotally connected at 41 to an extension 20a of the ring 20, the 60 socket portion being, preferably, rectangular in cross section. Mounted within the socket portion for sliding movement longitudinally thereof is a second socket member 42 also rectangular in cross section which member 65 carries a coil spring 43. The member 42 is

provided on one side with a longitudinally extending slot 44. The guide member proper is shown at 45 and is provided with a shank 46 having a transverse pin 47 which projects through the slot 44. The inner end of the shank is engaged by the spring 43, which tends to maintain it normally projected, the pin 47 limiting the movement of the shank in both directions. The second socket member 42 is adjustable in the socket 40 and is main- 70 tained in any desired adjusted position by means of a screw 48.

The guide is adjusted relative to the pen by means of a toggle construction 49 which comprises two pairs of links connected with the guide socket 40 and the lower pen nib 22 at 50 and 51, respectively. These links are connected at their opposite ends with threaded sleeves 52 and 53 through which extends a threaded rod or adjusting screw 54. It will be understood that by turning the screw 54 the links are drawn together or spread apart to adjust the position of the guide relative to the pen or applicator.

In Figs. 6 and 7 we have shown a modified form of guide in which the guide is bodily adjustable toward and from the pen. The lowermost pen nib 22 is provided with a pair of depending rods 55 secured at their upper ends at 56 to the pen nib and being bridged at their lower ends preferably by a horizontal bar 57. The guide device of these figures comprises a socket member 58 having on its opposite sides slots 59 and on its inner side with an apertured lug or projection 60 and a slotted lug or projection 61. Positioned within the socket is a coil spring 62 which engages the rear end thereof and the inner end of a stem or plunger 63 which carries the 105 guide element proper 64 which may be in the form of a ring as shown. The stem 63 is provided with a pin 65 projecting through the slots 59. It will thus be seen that the guide is bodily adjustable toward and from the pen and slides along the rods 55, and is maintained in any desired adjusted position by means of an adjusting screw 66 which when rotated expands or contracts the slotted lug or projection 61 causing it to release or grip the rod 55 with which it is in engagement.

When applying a stripe along or adjacent the belt panel BP of the panel B, the guide 45 or 64 will be adjusted in proper position so as to travel along the belt panel moulding. The position of the stripe with relation to the moulding BP will be determined by the relative positions of the guide and applicator.

We claim:

1. In a striping device for automobile bodies, a body portion having a reservoir, a striping applicator connected with said reservoir, a yieldable guide pivotally connected to the body portion to swing into various ad- 125 justed positions with respect to said appli- 130

cator, and means for maintaining the guide in adjusted position.

2. In a striping device of the class described, a reservoir for striping fluid, an applicator communicating therewith, a yieldable guide engageable with the body to be striped, and means for supporting said guide for adjustment about the longitudinal axis of the applicator.

10. In a striping device of the class described, a reservoir for striping fluid, an applicator, a feed conduit from the reservoir into said applicator, a guide engagable with the body to be striped for guiding the device in its movement, and means for adjusting said guide with respect to the reservoir into positions at different sides of said feed conduit.

20. In a striping device of the class described, in combination, a reservoir for striping fluid, an applicator communicating therewith for forming a stripe, a guide adapted to engage a part of the surface to be striped, and means for supporting said guide to permit adjustment thereof about the longitudinal axis of the applicator.

30. In a striping device of the class described, in combination, a reservoir for striping fluid, an applicator communicating therewith for forming a stripe, and a guide adapted to engage the body to be striped and rotatable about the longitudinal axis of the applicator.

35. In a striping device for automobile bodies or the like, a reservoir for striping fluid, an applicator communicating therewith for applying a stripe to the body, a guide adapted to pivotally engage a part of said body to guide the device, means for adjusting the guide toward and from said body, and for maintaining the guide in adjusted position, and means for yieldingly mounting the guide.

45. In a striping device for automobile bodies, a body portion, a reservoir, a handle for said device, a feed conduit extending forwardly from said body portion and communicating with said reservoir, a striping pen detachably connected with said body surrounding said feed tube and free to rotate thereabout, and guide means carried by said device for guiding the pen in use.

55. In a striping device for automobile bodies, a body portion, a reservoir, a feed tube communicating with said reservoir, a striping pen connected with said body surrounding said feed tube and free to rotate thereabout and adjustable resiliently supported guide means pivotally connected to said device for guiding the pen in use.

65. In a striping device for automobile bodies, a body portion, a reservoir, a feed conduit communicating with said reservoir, a striping applicator connected with said body surrounding said feed tube and free to ro-

tate thereabout, and guide means carried by said applicator and rotatable therewith for guiding the same in use.

10. In a striping device for automobile bodies, a body portion, a reservoir, a feed conduit communicating with said reservoir, a striping applicator connected with said body surrounding said feed tube and free to rotate thereabout, guide means carried by said applicator for guiding the same in use, and means for adjusting said guide means relative to said applicator.

11. In a striping device for automobile bodies, a body portion, a reservoir, a feed tube communicating with said reservoir, a striping applicator connected with said body surrounding said feed tube and free to rotate thereabout, guide means carried by said body portion for guiding the same in use, and means for adjusting said guide means bodily relative to said applicator.

12. In a striping device for automobile bodies, a body portion, a reservoir, a feed tube communicating with said reservoir, a striping pen connected with said body surrounding said feed tube and free to rotate thereabout, a frame carried by said pen and rotatable therewith, and a guide carried by the frame for guiding the pen in use, said guide being bodily movable thereon toward and from the pen.

13. In a striping device for automobile bodies, a body portion, a reservoir, a feed tube communicating with said reservoir, a striping pen connected with said body surrounding said feed tube and free to rotate thereabout, a frame carried by the said pen and rotatable therewith, a guide carried by said frame for guiding the pen in use, said guide being bodily adjustable thereon toward and from the pen, and means for locking the guide in adjusted position.

14. In a striping device for automobile bodies or the like, a reservoir for striping fluid, an applicator for forming a stripe, a conduit for supplying fluid to the applicator from said reservoir, means for supporting said applicator to turn about the longitudinal axis of said conduit, and guide means carried by said applicator for guiding the applicator in use.

In testimony whereof we affix our signatures.
